UNITED STATES PATENT OFFICE.

WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

PANTOGRAPH-TROLLEY.

1,354,134.

Specification of Letters Patent. Patented Sept. 28, 1920.

Application filed November 29, 1915. Serial No. 64,043.

To all whom it may concern:

Be it known that I, WILLIAM SCHAAKE, a citizen of the United States, and a resident of Pittsburgh, in the county of Allegheny and State of Pennsylvania, have invented a new and useful improvement in Pantograph-Trolleys, of which the following is a specification.

My invention relates to trolleys and particularly to pantograph trolleys which are raised by fluid-pressure mechanisms and are lowered by the action of gravity.

One object of my invention is to provide a pantograph trolley which shall be mounted on shafts and counterbalanced thereon by resilient members so that the fluid-pressure mechanisms, in raising the trolley, will need only to supply the contact pressure, pressure to compensate for friction of the moving parts and pressure to overcome the unbalanced weight of the trolley.

Another object of my invention is to provide a pantograph trolley which shall be raised by a fluid-pressure mechanism that is resiliently and flexibly connected to the pantograph frame.

More specifically, the object of my invention is to provide a pantograph trolley which is mounted upon shafts having cams mounted thereon, certain of which are resiliently and flexibly connected to fluid-pressure mechanisms for raising the trolley and others of which are connected to resilient members that counterbalance a portion of the weight of the trolley on the shafts.

In the accompanying drawings illustrating my invention, Figure 1 is a diagrammatic plan view, and Fig. 2 is an elevation of a pantograph trolley constructed in accordance with my invention. Figs. 3 and 4 are modifications of the fluid-pressure mechanism.

The pantograph trolley illustrated in the drawings comprises a current collector 2, a frame 3 that is supported upon shafts 4 and 5 and is adapted to turn therewith and upon which the current collector 2 is mounted, and fluid-pressure mechanisms 6 and 7 which are respectively connected to the shafts 4 and 5 for raising the trolley. The weight of the frame 3 is counterbalanced by a plurality of resilient members 8 and 9 which are respectively connected to the shafts 4 and 5. The resilient members 8 and 9 are preferably coil springs under tension, but such a structure is not essential to my invention. The

pantograph frame 3 has an upper portion comprising rods 10, 11, 12 and 13 having their upper ends joined to the current collector 2 and having their lower ends joined to hinge connectors 14, 15, 16 and 17, and a lower portion comprising rods 18, 19 and 20 having their upper ends joined to the hinge connectors 14 and 15 and their lower ends rigidly connected to the shaft 5 to turn therewith, and rods 21, 22 and 23 having their upper ends joined to the hinge connectors 16 and 17 and their lower ends rigidly connected to the shaft 4 to turn therewith.

The shafts 4 and 5 are mounted upon angle bars 24, 25, 26 and 27 which are mounted upon the insulated supports 28. The shaft 4 has cams 29 and 30 rigidly mounted thereon to turn therewith and respectively connected to the resilient member 8 and the fluid-pressure mechanism 6. The shaft 5 has cams 31 and 32 mounted thereon to turn with it and respectively connected to the resilient member 9 and to the fluid-pressure mechanism 7. Tie rods 33 and 34, for causing the shafts 4 and 5 to turn together, are joined to the upper and lower sides thereof by levers 35 which are rigidly mounted upon the shafts.

The resilient member 8, which is preferably a coil spring under tension, has one end joined to the cam 29 and its other end joined to an arm 36 which is mounted on the angle bar 26. The resilient member 9, which is also preferably a coil spring under tension, has one end joined to the cam 31 and its other end joined to an arm 37 which is mounted on the angle bar 24. The resilient members 8 and 9 are made of such strength that they counterbalance a portion only of the weight of the frame on the shafts 4 and 5 so that the fluid-pressure mechanisms 6 and 7 need only overcome the friction of the moving members, contact pressure and the unbalanced weight of the frame.

The fluid-pressure mechanism 7 comprises a fluid-pressure cylinder 38 having an inlet port 39, a piston head 40 operating within said cylinder, a piston rod 41 which has one end pivotally connected to the piston head 40 and its other end connected to a resilient member 42, and a flexible member 43 which is preferably a chain that connects the resilient member 42 to the cam 32. The fluid-pressure mechanism 6 is composed of parts similar to those used in the construction of

the fluid-pressure mechanism 7 and are designated by like reference characters.

The fluid-pressure mechanism disclosed in Fig. 3 comprises a fluid-pressure cylinder 44 having an inlet port 45, a piston head 46 operating within the fluid pressure cylinder 44, a piston rod 47 having one end pivotally connected to the piston head 46 and its other end pivotally connected to a rod 48 which has one end connected to a resilient member 49 and its other end pivotally joined to a support 50. The fluid-pressure mechanism shown in Fig. 4 comprises a fluid cylinder 51 having an inlet port 52, a piston head 53, a piston rod 54 having one end pivotally joined to the piston head 54 and its other end pivotally connected to a rod 55 which has its other end pivotally connected to a support 56, and a resilient member 57 which is joined to the rod 55 intermediate its ends.

The mechanisms which have been designated as fluid-pressure mechanisms are operated by vacuum which is imparted to the cylinders 38 through the ports 39. The pantograph trolley 1, which is shown in a raised position, may be lowered by releasing the vacuum imparted to cylinders 38 of the fluid-pressure mechanisms 6 and 7, whereby the weight of the trolley 1, acting against the tension of the resilient members 8 and 9, will lower the trolley. In order to raise the trolley, the pressure within the cylinders 38 of the fluid-pressure mechanisms 6 and 7 is reduced, whereby the piston heads 40, operating through the piston rods 41, resilient members 42, flexible members 43 and the cams 32 and 30, will turn the shafts 4 and 5 to raise the trolley.

Obviously, the apparatus of my invention may be varied considerably without departing from the spirit and scope of my invention, and I desire, therefore, that only such limitations shall be imposed as are indicated in the appended claims.

I claim as my invention:

1. In a trolley, the combination with a pantograph frame, a contact shoe mounted upon said frame, and shafts for supporting said frame, of cams mounted upon said shafts, and vacuum-actuated mechanisms comprising cylinders, vacuum-actuated pistons operating within said cylinders and flexible connections between said cams and said pistons.

2. In a trolley, the combination with a pantograph frame, and a contact shoe mounted thereon, of a vacuum-actuated mechanism for raising said frame, and flexible and resilient means for connecting said mechanism to said frame.

3. In a trolley, the combination with a pantograph frame, shafts for supporting said frame and for raising the same when rotated, and cams mounted upon, and rotating with, said shafts, of a fluid-pressure mechanism for rotating said shafts to raise said frame comprising fluid-pressure cylinders, pistons operating within said cylinders and resilient and flexible members for connecting said pistons to said cams.

4. In a trolley, the combination with a pantograph frame, shafts for supporting said frame and for raising the same when rotated, and cams mounted upon, and rotating with, said shafts, of a fluid-pressure mechanism for rotating said shafts to raise said frame and comprising fluid-pressure cylinders, pistons operating within said cylinders, piston rods pivotally connected to said pistons, and resilient and flexible members for connecting said piston rods to said cams.

5. In a trolley, the combination with a pantograph frame, of a fluid-pressure mechanism for raising said frame, resilient and flexible members for joining said mechanism to said frame, and resilient means initially tending to raise said frame to counterbalance only a portion of said frame.

6. In a trolley, the combination with a contact shoe and a pantograph frame, of a vacuum mechanism for raising said frame and said shoe, and resilient means for counterbalancing only a portion of the weight of said shoe and said frame.

7. In a trolley, the combination with a pantograph frame, a contact shoe mounted upon said frame, and shafts for supporting said frame and for raising the same when rotated, of cams mounted upon said shafts, resilient members under tension connected to certain of said cams, and vacuum-actuated mechanisms connected to the remaining cams.

8. In a trolley, the combination with a pantograph frame, a contact shoe mounted upon said frame, shafts for supporting said frame and for raising the same when rotated, and cams mounted upon, and rotating with, said shafts, of resilient means connected to certain of said cams and under stress for assisting to raise said frame, and fluid-actuated mechanisms for raising said frame and comprising fluid cylinders, pistons operating within said cylinders and resilient and flexible members for connecting said pistons to the remaining cams.

In testimony whereof, I have hereunto subscribed my name this 24th day of Nov., 1915.

WILLIAM SCHAAKE.
